CLAIM

The ornamental design for a combined ring and insert with faceted stones, as described and shown.

DESCRIPTION

FIG. 1 is a front perspective view of an embodiment of a combined ring and insert with faceted stones according to the new design;

FIG. 2 is a front plan view thereof;

FIG. 3 is a back plan view thereof;

FIG. 4 is a right side view thereof;

FIG. 5 is a left side view thereof;

FIG. 6 is a top plan view thereof;

FIG. 7 is a bottom plan view thereof;

FIG. 8 is a lower perspective view thereof, illustrating the insert in place on the ring;

FIG. 9 is a front perspective view of another embodiment of a combined ring and insert with faceted stones according to the new design;

FIG. 10 is a front plan view thereof;

FIG. 11 is a rear plan view thereof;

FIG. 12 is a right side view thereof;

FIG. 13 is a left side view thereof;

FIG. 14 is a top plan view thereof;

FIG. 15 is a bottom plan view thereof; and,

FIG. 16 is a lower perspective view thereof, illustrating the insert in place on the ring.
